WIRE STRETCHER

Filed March 5, 1923

2 Sheets-Sheet 2

UNITED STATES PATENT OFFICE.

JAMES M. MARTIN, OF HARTLEY, ARKANSAS, ASSIGNOR OF ONE-HALF TO WILLIAM S. CAPEHEART, OF VANDERVOORT, ARKANSAS.

WIRE STRETCHER.

Application filed March 5, 1923. Serial No. 622,887.

To all whom it may concern:

Be it known that JAMES M. MARTIN, a citizen of the United States, residing at Hartley, in the county of Polk and State of 5 Arkansas, has invented certain new and useful Improvements in Wire Stretchers, of which the following is a specification.

This invention relates to a wire stretcher and has for its principal object to provide 10 a means whereby the stretching of a wire fence may be facilitated.

Another object of the invention is to provide a wire stretcher of the above mentioned character, which is of a construction where- 15 by the same may be easily set up for stretching a wire fence and renders the same collapsible, so that the wire stretcher may be folded up and transported from place to place.

20 A still further object of the invention is to provide a wire stretcher of the above mentioned character, which is simple in construction, inexpensive, strong and durable and well adapted for the purpose for which 25 it is adapted.

Other objects and advantages of this invention will become apparent during the course of the following description.

In the accompanying drawings forming 30 a part of this specification, and in which like numerals designate like parts throughout the same:-

Figure 1 is a side elevation showing the wire stretcher in use.

35 Figure 2 is an end elevation of the same.

Figure 3 is a top plan view.

Figure 4 is a detail view showing the construction of the brace bar.

Figure 5 is a detail view showing the construction of the wire fence clamping means.

In the drawings wherein for the purpose of illustration is shown the preferred embodiment of my invention, the numeral 1 designates the base upon which is supported 40 my wire stretcher and the forward end of the base is hollowed out so as to provide a curve portion 2 whereby the base may fit snugly in position against a fence post 3.

A brace 4 is hingedly mounted at its lower 45 end to the base 1 as shown more clearly at 5 in Fig. 1 of the drawings. The upper end of the brace 4 is also hollowed out to provide a curved upper end 6 similar to the curved forward end 2 of the base 1 for the purpose

of permitting a positive fit against the upper 55 end of the fence post 3 to which the wire fence is stapled. This brace 4 is provided with a longitudinal slot 7 therein for the purpose hereinafter to be more fully de- 60 scribed and is furthermore provided with spaced apertures 7' along its longitudinal side edges.

Adapted to be detachably supported in the aperture 7' formed in the brace 4 are a number of flanged spools 8. These flanged 65 spools 8 are supported upon suitable pins 8' which are adapted to fit snugly in the apertured opening 7'.

A pair of spaced angular lugs 9 and 10 are secured to the base 1 adjacent its forward end 2 and are held in position upon the base 1 by any suitable fastening means 11. The upper ends of the angular lugs 9 and 10 are provided with registering apertures 12 and 13 and these registering apertures 12 70 and 13 communicate with the apertured end 75 of a stretcher bar 14.

This stretcher bar 14 is supported upon the base 1 in such a manner that its apertured end 15 is adapted to be received between the spaced angular lugs 9 and 10 and in such a manner that the apertured opening in the lower end of the stretcher bar 14 will register with the apertures 12 and 13 formed in the angular lugs carried by the 80 base 1. A suitable pintle for bolt 16 is adapted to pass through the apertures 12, 13 and 15 respectively and receive the nut 17 upon its threaded end for pivotally supporting the stretcher bar. The stretcher bar 90 14 is provided with a plurality of spaced hooks 18 on its inner longitudinal side and is also provided with a hook 19 on the opposite side adjacent the top thereof.

Before the stretcher bar 14 is placed in 95 position upon the base 1 it is adapted to be passed through the longitudinal slot 7 formed in the brace 4 so that the same is slidably associated therewith.

A plate 20 is secured at the opposite end 100 of the base 1 and is wider than the base 1 so as to have its side edges extending a slight distance beyond each side of the base 1. The plate 20 is provided with a pair of upstanding spaced ears 21 and 22 respectively and these ears 21 and 22 are provided with apertures 23 and 24 in their upper ends. A bolt or shaft 25 is adapted to be received 105

in the apertured ends 23 and 24 of the spaced upstanding ears 21 and 22 and this bolt 25 carries a suitable reel or drum 26.

This drum 26 is provided with a flange 27 intermediate its ends whereby the reel is divided into a drum section or cable receiving means 26 and a ratchet wheel 28 on the opposite side of the flange 27. A ratchet lever 29 is pivotally mounted upon the shaft 25 and carries a double acting pawl 30 which is pivoted at 31 to the lever 29 for engagement with the ratchet wheel 28 carried by the shaft 25. The double acting pawl 30 is provided so as to cause the ratchet wheel 28 and the drum 26 associated therewith to be rotated in either direction, as the case may be.

A pair of auxiliary spaced lugs 32 and 33 are mounted upon the plate 20 and these auxiliary spaced lugs 32 and 33 are provided with registering openings 34 and 35 for the purpose of receiving a pin 36. This pin 36 pivotally supports a locking finger or lug 37 which has a square end portion 38 which is adapted to engage the cogs formed in the ratchet wheel 28 for holding the same in position so as to prevent the unwinding of the drum and cable.

A small pulley 39 is pivotally mounted upon the plate 20 and is provided at its opposite end with the apertured eye 40 for receiving and securing one end of a suitable cable or rope 41. The pulley 39 is provided with the usual pulley wheel so as to receive the cable 41 and act as a guide for the cable. A block or pulley frame 42 having a hook 43 at its upper end for supporting and engaging the hook 19 carried by the upper end of the stretcher bar 14 is adapted to be held in a suspended position thereon and is provided with a pair of pulley wheels 44 for the purpose of receiving and guiding the cable 41. The opposite end of the cable 41 is secured to the drum 26 and is adapted to be wound thereon in a manner that will be hereinafter more fully described.

The fence wire clamping means associated with my wire stretcher comprises a clamp 45 and provided in the enlarged end of the clamp 45 is an enlarged opening 46. In the opposite end of the clamp 45 is secured one end of a chain 47 and the opposite end of the chain 47 or any of the links comprising the chain 47 is adapted to be supported upon the stretcher bar 14 by means of engagement with the spaced hooks 18 arranged in the inner longitudinal side of the stretcher bar 14. A lug 48 is provided in the enlarged end of the clamp 45 so as to have its forward end or free end 49 which is flanged to extend into the aperture 46 provided in the enlarged end of the clamp 45. On the face of the clamp 45 adjacent the lug 48 I pivotally mount or support thereon at 50, a latch 51 and this latch 51 is adapted to swing upon

the clamp 45 for the purpose to be later described.

In order to hold the wire stretcher in a stationary position when in the process of stretching a wire fence, the plate 20 which is provided with the sides which extend beyond the sides of the base 1 is adapted to receive suitable anchoring stakes 52 and 53 respectively in apertures 54 and 55 respectively formed in the extended sides of the plate 20 and these stakes 52 and 53 are adapted to be driven into the ground for holding the wire stretcher in position. The stretcher bar 14 is provided with the hooks 18 on its inner longitudinal side edge for the purpose of receiving the linked chain 47 which carries the clamp 45 at its forward end and as many of these clamps 45 may be used as is necessary to accommodate and stretch each strand of wire comprising the wire fence so that the wire fence may be stretched in one operation, that is to say each strand of wire is stretched simultaneously with the other strand so it is not necessary for the operator to first attach the wire stretcher to one strand of wire and after the same has been stretched to then release the same and place it upon the next strand and repeat the same process.

In use, the wire stretcher is set up in position as shown in Figure 1 of the drawings and the strand of the wire fence 56 are passed through the enlarged aperture formed in the clamp 45 and is bent around the free end 49 of the lug 48 which extends into the enlarged opening 46 of the clamp 45. The wire 56 is then passed through the aperture 46 so as to come out upon the face of the clamp 45 and the latch 51 is then swung over the free end of the strand of wire 56 and frictionally holds and clamps the wire upon the clamp 45. When in this position the clamp 45 is hooked onto the hook 18 carried by the stretcher bar 14 and the pulley frame 42 is then hooked upon the opposite side edge of the stretcher 14 upon the hook 19 and the lever 29 is then operated so that the pawl 30 will engage the ratchet wheel 28 so as to cause the drum 26 to wind the cable thereon and while in such operation the stretcher bar 14 will be caused to move or swing rearwardly and forward towards the drum 26 and while in such movement will cause the strand of wire 56 to be stretched. The locking finger or lug 37 will hold the drum in position so as to prevent the unwinding of the cable upon the drum 26 and thereby hold the stretcher bar 14 in its adjusted or stretched position. In this manner the operator can staple the strands of the fence wire 56 to the fence post 3 more easily and quickly. The spools 8 which are arranged on the side of the brace 4 are adapted to act as guide rollers for the fence wire when the same is being stretched and fur-

thermore keep the strands of wire in proper position while the same are being stretched, so as to assure the proper alinement of the strands of wire 56 when the same are about 5 to be stapled or secured to the fence post 3.

It will be seen from the foregoing description that a wire fence stretcher has been provided wherein the strands of the wire fence may be stretched simultaneously and more 10 quickly and easily furthermore, each strand of wire is so stretched as to take up any slack which may occur in the wire fence.

The structure of my wire fence stretcher enables it to be readily collapsed and set 15 up in position for use and does not necessitate the employment of a number of men to operate the same. Furthermore, its efficiency can be readily appreciated and its 20 simplicity in operation also renders it valuable for use in stretching wire fences of various kinds.

From the foregoing description of the construction of my improved apparatus, it will be seen that I have provided a simple, inexpensive and efficient means for carrying out 25 the objects of the invention, and while I have particularly described the elements best adapted to perform the functions set forth, it is obvious that various changes in 30 proportion, form and in the minor details of construction may be resorted to without departing from the spirit or sacrificing any of the principles of the invention.

What I claim as new and desire to secure 35 by Letters Patent is:—

1. A wire fence stretcher including a base, a stretcher bar pivotally mounted on said base at one end thereof, a brace pivoted to said base and slidably associated with said 40 stretcher bar, fence wire clamping means carried by said stretcher bar, and means on the opposite end of said base for operating said stretcher bar.

2. A wire fence stretcher including a base, a stretcher bar pivotally mounted on said base at one end thereof, a brace pivoted to said base, said brace having a longitudinal slot for receiving the said stretcher bar, fence wire supporting members on the side 50 edges of said brace, and fence wire clamping means carried by the fence stretcher bar, and means on the opposite end of said base for operating said stretcher bar.

3. A wire fence stretcher, including a 55 base, a stretcher bar pivotally mounted on

said base at one end thereof, a brace pivoted to said base, said brace having a longitudinal slot for receiving the said stretcher bar, fence wire supporting members on the side edges of said brace, fence wire clamping means carried by said stretcher bar, a drum on the opposite end of said base, a cable on said drum and associated with said 60 stretcher bar, an operating lever for winding said cable on said drum, and operating the stretcher bar.

4. A wire fence stretcher including a base, a stretcher bar pivotally mounted on said base at one end thereof, spaced hooks on the inner longitudinal side of said stretcher bar, 70 a brace pivoted to said base, said brace having a longitudinal slot for receiving said stretcher bar, fence wire supporting members spacedly mounted on side edges of said brace, fence wire clamping means associated 75 with the hooks on said stretcher bar, a plate on the opposite end of said base, a windlass supported on said plate, a pulley wheel swivelly mounted on said plate, a second pulley carried by the upper end of the 80 stretcher bar, a cable secured to the first mentioned pulley and associated with the two pulleys and secured at its opposite end to the windlass for operating the stretcher bar and wire fence clamping means. 85

5. A wire fence stretcher including a base, a stretcher bar pivotally mounted on said base at one end thereof, spaced hooks on the inner longitudinal side of said stretcher bar, a brace pivoted to said base, said brace having a longitudinal slot for receiving said 90 stretcher bar, fence wire supporting members spacedly mounted on said edges of said brace, fence wire clamping means associated with the hooks on said stretcher bar, a plate on the opposite end of said base, a windlass supported on said plate, a pulley wheel swivelly mounted on said plate, a second pulley carried by the upper end of the 95 stretcher bar, a cable secured to the first mentioned pulley and associated with the two pulleys and secured at its opposite end to the windlass for operating the stretcher bar and wire fence clamping means, and anchoring means associated with the plate 100 for holding the wire stretcher in a stationary position. 105

In testimony whereof I affix my signature.

JAMES M. MARTIN.
